[57] **CLAIM**

The ornamental design for an animal feces retriever, as shown and described.

DESCRIPTION

FIG. 1 is a front-left side perspective view of an animal feces retriever according to my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;
 FIG. 8 is a front-left side perspective view of the animal feces retriever in use;
 FIG. 9 is a front-left side perspective view of a second embodiment of my new design;
 FIG. 10 is a front elevational view thereof;
 FIG. 11 is a rear elevational view thereof;
 FIG. 12 is a left side elevational view thereof;
 FIG. 13 is a right side elevational view thereof;
 FIG. 14 is a top plan view thereof;
 FIG. 15 is a bottom plan view thereof; and
 FIG. 16 is a front-left side perspective view of the second embodiment in use.
